AMPLIFICATION SYSTEM

John L. Weston, East Orange, N. J., assignor to
Wired Radio, Inc., New York, N. Y., a corpora-
tion of Delaware

Application March 8, 1934, Serial No. 714,661

5 Claims. (Cl. 179—171)

My invention relates to systems for the amplification of electrical energy and particularly to systems employing space discharge tubes where the energy to be amplified is too great for a single tube of convenient size.

In amplification systems, when the amount of energy to be amplified is too great for a single space discharge tube it is customary to connect the tubes in a parallel arrangement; that is, the

10 input elements of the tubes are parallel-connected to the input circuit and the output elements are parallel-connected to the output circuit. A modification of this method is to connect pairs of the tubes in push-pull and these pairs in parallel, to effect the elimination of distortion introduced by the tubes. It has been found in the operation of such circuits, however, that, unless the input circuits deliver substantially equal voltages to the input elements of each tube, some tubes are forced to operate under 15 overload conditions, thereby causing distortion and damage to the tubes and associated circuits.

One of the objects of my invention is to provide means for operating space discharge tubes in 20 parallel amplifying circuits with regulation of the amount of energy amplified by each tube.

Another object is to produce a system of connection for space discharge tubes to provide automatic regulation of currents.

30 A further object consists in producing means for preventing any single space discharge tube, or pair of tubes in an amplifier circuit from assuming more than its share of the energy being amplified.

35 A still further object is to provide means for obtaining such regulation without the use of complicated apparatus.

These and other desirable objects will be apparent from the following description taken in 40 conjunction with the accompanying drawing which is a diagrammatic representation of a preferred embodiment of my invention.

Referring to the drawing, four space discharge tubes, 3—6, are shown connected to two input 45 transformers 1 and 2. Transformer 1 comprises a primary winding 11, and two secondary windings 7 and 8. Transformer 2 comprises a primary winding 18 and two secondary windings 9 and 10. The secondary windings 7 and 8 of transformer 1, are respectively connected, in push-pull 50 relationship, between the control electrodes and cathode elements of tubes 3 and 4. In parallel with the windings 7 and 8 are resistors 12 and 13, which, in conjunction with a source of voltage 14, 55 maintain the control electrodes of tubes 3 and 4

at a fixed operating potential. Tubes 5 and 6 are likewise connected in push-pull to the secondary windings 9 and 10 of transformer 2. Resistors 15 and 16 connect a source of voltage 17 to the control electrodes of tubes 5 and 6. Primary winding 18 of transformer 2 is connected in parallel with primary winding 11 of transformer 1 to the source of energy to be amplified.

Sources of voltage 19 and 20 are provided for supplying heating current to the cathodes of 10 tubes 3—6. The anode or output circuits of tubes 3 and 5 include the primary windings 25 and 26 of a transformer 21 and a source of voltage 29 to form a push-pull connection. The output or anode circuits of tubes 4 and 6 include the primary windings 23 and 24 of a transformer 22 and a source of voltage 29, to also form a push-pull connection. The secondary windings 27 and 28 of transformers 21 and 22 are parallel-connected to a load circuit 30 which may be any means for 20 the utilization of amplified energy.

In the operation of the amplifying system of my invention, electrical oscillations from the source 14, at audible or super-audible frequencies, induce voltages in the secondary windings 7—10, 25 transformers 1 and 2, which act on the control electrodes of tubes 3—6, to cause corresponding variations in the anode currents of these tubes. The control electrodes of tubes 3—6 are maintained at their proper operating potentials 30 through resistors 12, 13, 15 and 16, which serve to conduct any current that may flow in the input circuit without the loss that would be introduced by the secondary windings 7—10.

In the output circuits of tubes 3—6 the varying 35 anode currents pass through the primary transformer windings 23, 24, 25 and 26 to induce voltages in the secondary windings 27 and 28 causing a varying current to flow therein and in the load 30. Under normal conditions, that is, under 40 conditions of equal input voltages on the control electrodes of tubes 3—6, and equal amplification in said tubes, the currents in the primary windings 23—26 are equal and the system operates as 45 desired, faithfully reproducing, in increased values, the currents of source 14. In actual operation however, it may happen that one of the pairs of tubes, either 3 and 4 or 5 and 6, receives on its control electrodes higher input 50 voltages than the other pair, in which case more current tends to flow in the anode, or output circuits of the tubes so affected. In this preferred embodiment of my invention I obtain regulation for this condition by a novel manner 55

of connecting the anodes of the tubes 3—6, to the output transformers 21 and 22.

If grouped according to their input circuits, the tubes 3 and 4 constitute a pair, and the tubes 5 and 6 a second pair. In ordinary practice the tubes of these pairs would have common output transformers. In my invention, however, I cross the connections to the output transformers so as to form two new pairs according to output circuits. These pairs comprise tubes 3 and 5 and 4 and 6 as determined by the connections to transformers 21 and 22, respectively.

The result of such output connections is that, when a condition of unbalance exists in the input circuits, unequal loads are placed in the circuits of the primary windings of transformers 21 and 22. Hence, when tubes 3 and 4, say, receive a higher input voltage than tubes 5 and 6, their output windings 26 and 24 are inductively coupled to the windings which are in the circuits of tubes 5 and 6. Since tubes 5 and 6 are receiving a relatively low input voltage their anode resistances are relatively high. Therefore, instead of two low impedance paths being connected to the two windings of a single push-pull transformer, as is the usual case, there are coupled inductively a high impedance and low impedance path in each of the transformers 21 and 22, with resultant decrease of current in the windings 26 and 25 connected to the tubes 3 and 4. The greater the difference between input voltages of the two pairs—3 and 4, and 5 and 6, the greater is the damping effect due to the arrangement of my invention.

Although I have shown a specific embodiment of my invention, it is to be understood that modifications may be made by those skilled in the art, which are to be within the scope of the appended claims.

What I claim as new and original and desire to secure by Letters Patent of the United States is:

1. In a system for the amplification of electrical energy, two pairs of space discharge tubes, input transformers each comprising primary windings and divided secondary windings, said primary windings being connected in parallel with the directional changes in their ampere turns in opposition, said secondary windings being respectively connected to the input elements of each pair of said tubes in balanced push-pull relation, and output transformers each comprising secondary windings and divided primary windings, said primary windings being connected respectively to the output elements of one tube from each of said pairs of tubes and said secondary windings being connected in parallel with the directional changes in their ampere turns in opposition.

2. An amplifying system comprising, two pairs of space discharge tubes, input transformers having primary windings and plural secondary windings for each of said pairs of tubes, said primary windings being connected in parallel with the directional changes in their ampere turns in opposition, connections from said plural secondary windings to said tubes in pairs respectively, output transformers having secondary windings and plural primary windings, said primary windings being connected to one tube in each of said pair of tubes respectively to form different pair groups and said secondary windings being con-

nected in parallel with the directional changes in their ampere turns in opposition.

3. In a system for the amplification of electrical energy, two pairs of space discharge tubes, input circuits therefor connected to said tubes in balanced push-pull relation, said input circuits of said pairs of tubes being connected in parallel in phase opposition, output transformers associated with each of said pairs of tubes respectively, each of said transformers being connected to one tube in each of the above mentioned pairs of tubes whereby the amount of energy amplified by one of said pairs of tubes is regulated by the amount of energy being amplified by another of said pairs of tubes.

4. In a system for the amplification of electrical energy, two pairs of space discharge tubes each having input and output circuits, input transformers for each of said pairs of tubes, each of said transformers comprising a primary winding and a plural secondary winding, said secondary windings of each of said transformers being connected in series and said secondary windings being included in the input circuit of each of said pairs of tubes respectively to form a pair of balanced push-pull input circuits, there being at least two such balanced input circuits each including a pair of said tubes, connections between the primary windings of said input transformers forming a parallel input circuit to said transformers in which the directional changes in the ampere turns of said primary windings are in phase opposition, a plurality of output transformers each comprising a secondary winding and plural primary windings, said primary windings of each of said output transformers being connected in series and each connected in the output circuit of one of each of said pairs of tubes whereby the operation of one of said pairs of tubes having a balanced input circuit is subject to control from another of said pairs of tubes having a similarly balanced input circuit and connections between the secondaries of said output transformers forming a parallel output circuit in which the directional changes of the ampere turns in said secondaries is in phase opposition for delivering energy uniformly amplified by said space discharge tubes.

5. A system for the amplification of electrical energy comprising, a first pair of space discharge tubes each having a grid, cathode and anode, a balanced push-pull input circuit for said pair of tubes whereby the potentials applied to the grids of said tubes are in phase opposition, a second pair of space discharge tubes each having a grid, cathode and anode, a balanced push-pull input circuit for said second pair of tubes whereby the potentials applied to said grids are in phase opposition, means combining said input circuits whereby the potentials applied to the grids of said first pair of tubes are in phase opposition respectively with the potentials applied to the grids of the corresponding tubes of said second pair of tubes and output transformers each comprising secondary windings and divided primary windings, said primary windings being connected respectively to the output elements of one tube from each of said pairs of tubes and said secondary windings being connected in parallel with the directional changes in the ampere turns in opposition.

JOHN L. WESTON.
